CLAIM

The ornamental design for a beach carrier, as shown and described.

DESCRIPTION

FIG. 1 is a right side elevational view of a beach carrier showing my new design, the left side being a mirror image thereof;

FIG. 2 is a top plan view thereof;

FIG. 3 is a bottom plan view thereof;

FIG. 4 is a rear elevational view thereof;

FIG. 5 is a front elevational view thereof; and,

FIG. 6 is a fragmentary view thereof showing an alternative handle, the rest of the structure being identical to that described in FIGS. 1-5.

FIG. 1

FIG. 4

FIG. 5
